GOLF CLUB HEAD

John Robert Lysaght, Cincinnati, Ohio, assignor to Brunswick Corporation, Chicago, Ill., a corporation of Delaware

Filed May 21, 1968, Ser. No. 12,029

Term of patent 14 years

Int. Cl. D21—03

U.S. Cl. D34—5

FIGURE 4 is a rear elevation view of another form of my golf club head wherein the sole has a double step;

In both forms, the face of the club is flat having a configuration like the silhouette of the blade in FIG. 1.

I claim:

The ornamental design for a golf club head, substantially as shown and described.
